EARRING

Paul Gutenstein, New York, N. Y.

Application July 6, 1950, Serial No. 10,978

Term of patent 3½ years

(Cl. D45—9)

To all whom it may concern:

Be it known that I, Paul Gutenstein, a citizen of the United States of America, residing at 114 East 90th St., New York, N. Y., in the county of New York, and State of New York, have invented a new, original, and ornamental Design for an Earring, of which the following is a specification, reference being had to the accompanying drawing, forming part thereof.

In the drawing

Fig. 1 is a front elevational view of an earring, showing my new design;

Fig. 2 is a side elevational view thereof, and

Figs. 3 and 4 are rear elevational and bottom plan views, respectively, of the earring.

I claim:

The ornamental design for an earring, substantially as shown and described.

PAUL GUTENSTEIN.
